UNITED STATES PATENT OFFICE.

BERNARD A. KANTROWITZ, OF NEW YORK, N. Y.

FILTER.

1,042,233.

Specification of Letters Patent.

Patented Oct. 22, 1912.

Application filed October 22, 1910. Serial No. 588,435.

To all whom it may concern:

Be it known that I, BERNARD A. KANTROWITZ, a subject of the Czar of Russia, residing at New York, in the county of New

5 York and State of New York, have invented new and useful Improvements in Filters, of which the following is a specification.

This invention relates to filters, and its object is to provide a simple and cheap device which can be easily taken apart to clean

10 same or make any necessary repairs as will be more fully described in the following specification set forth in the claims and illustrated in the drawings, wherein,—

15 Figure 1 is a side elevation. Fig. 2 is a vertical section of same. Fig. 3 is a plan view of the lower part of the filter.

This filter consists of a globular shell divided into two parts, 5 and 6, the shell 5 having an inlet 7 and screw threads 8 therein to secure same to faucets 9. The lower portion of the part 5 is provided with a perforated diaphragm 10, while around same is a groove 11, adapted to receive a packing

20 12. This upper portion 5 also has an annular flange 13 upon which is fitted a ring 14, having screw threads 15 by which it is secured to the upper end of the lower portion 6. This lower portion also has a flange

25 16 adapted to enter the groove 11 and fit against the packing 12. The upper side of this portion is also provided with a perforated diaphragm 17, and between this and the diaphragm 10 a packing of fabric may 30 be inserted in order to prevent the passage of impurities through the filter as the water works through the strainer 18.

When the filter has been some time in use and a great amount of dirt and sand collected in the upper part, the lower portion may be removed by unscrewing the ring 14 and separating the two parts of the filter. This does not necessitate the elimination of the ring 14, but simply the unscrewing of same when it will be possible to remove the lower part and take out the packing 18 for cleansing when the dirt may also pass through the perforations in the upper diaphragm. In the center of the diaphragm

10 a blank space is permitted to remain in 50 order to diffuse the water as it flows through the opening 7 and causes same to run through the perforations evenly.

It is obvious that other alterations and modifications may be made in the details 55 without departing from the essential features above described.

The ring 14 is provided with studs 19 for unscrewing same while similar studs 20 project from the sides of the part 6 so that it 60 might be turned in a different direction from the ring when it is desired to unscrew the two or screw them together. The inlet 7 is surrounded by a gasket 7' to prevent the 65 leakage of water.

The object of this device is to provide a filter, which will not accumulate dirt as when the filtering pad becomes filled with dirt and impurities it may be thrown away, and a new and clean one substituted. Pads 70 of lint have been found most serviceable and inexpensive so they are the most effectual in preventing the passage of dirt, and cost but little.

This construction provides a filter using 75 no rivets, screws or bolts which are apt to become loosened or lost and often rust, and are difficult to unscrew when it is desired to renew the pad or strainer.

What I claim as new and desire to secure 80 by Letters Patent is,—

In a filter, the combination with a shell comprising two hemispheric sections, of perforated diaphragms at the larger ends of the sections, a filter disk adapted to fit between the diaphragms, a ring swiveled on one of the sections and having threads to engage the other section, means for rotating the ring and compressing the filter between the diaphragms and a flange on one of the 90 diaphragms and fitting in a groove in the other.

In testimony whereof I affix my signature in presence of two witnesses.

BERNARD A. KANTROWITZ.
